UNITED STATES PATENT OFFICE.

SAMUEL J. BRIGHTON, OF FAIRFIELD, IOWA.

DESIGN FOR A STOCK-IMPLEMENT CUTTING-HEAD AND HANDLE-STUB.

SPECIFICATION forming part of Design No. 34,410, dated April 23, 1901.

Application filed February 26, 1901. Serial No. 49,001. Term of patent 14 years.

To all whom it may concern:

Be it known that I, SAMUEL J. BRIGHTON, a citizen of the United States, residing at Fairfield, county of Jefferson, and State of Iowa, have invented and produced a new and original Design for a Stock-Implement Cutting-Head and Handle-Stub Relating to Stock-Marking, Antirooting, and Dehorning Devices; and I hereby declare the following to be a full, clear, and exact description thereof, reference being made to the accompanying drawings, forming a part hereof.

In the drawings, Figure 1 is a plan view of a cutting-head and handle-stub of my new and original design; Fig. 2, a view in side elevation of the same; Fig. 3, a section taken, as indicated, at line 3 of Fig. 1; and Fig. 4, a bottom plan view of the same.

As shown in the drawings, the leading or material feature of my design consists in a bifurcated head A, a handle-stub B, joined

thereto and offset from the plane thereof, and a cutting-blade C, forming, with the bifurcated head A, a closed loop.

In Fig. 1 the cutting-blade is shown with its central portion projecting to form a slightly-rounded apex or terminal a.

In Fig. 2 a pivotal point b is shown. Also, flanges b' are shown, connected with the outer vertical faces of the bifurcations of the head A, said flanges being located at the upper margins of said surfaces.

What I claim as new, and desire to secure by Letters Patent, is—

The design for a stock-implementation cutting-head and handle-stub herein shown and described.

SAMUEL J. BRIGHTON.

In presence of—

H. H. BRIGHTON,
E. E. LUCAS.
